UNITED STATES PATENT OFFICE

2,511,515

FOLDING CAMP STOVE

Frank W. Schmitt, Colorado Springs, Colo.

Application December 16, 1946, Serial No. 716,480

1 Claim. (Cl. 126—9)

1

This invention relates to a portable, collapsible camp stove, and has for its principal object the provision of a stove which can be quickly and easily assembled or disassembled, and which, when assembled, will form a convenient, highly efficient camp stove, and which, when disassembled, will occupy but a minimum of space for easy portability.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a perspective view of the improved, collapsible stove, erected and ready to use, with its top or frying plate removed;

Fig. 2 is a vertical cross-section therethrough, taken on the line 2—2, Fig. 5;

Fig. 3 is a top view, with the top plate removed;

Fig. 4 is a detail, enlarged section, illustrating the type of vertical corner joints employed on the improved camp stove;

Fig. 5 is a vertical, longitudinal section through the improved stove, taken on the line 5—5, Fig. 2;

Fig. 6 is a detail, perspective view of an element which may be used in the improved stove either as a fire grate or as a grill; and

Fig. 7 is a similar detail, perspective view, illustrating the ash pan of the improved stove.

The improved stove is more particularly intended for use as a camp stove, and is designed to be folded into a very small space so that it may be placed in the trunk or luggage compartment of an automobile.

The stove consists of eight parts, to wit, two side plates 10; a back plate 11, a front plate 12; an ash pan 13; a top plate 14; and two open grills, one of which serves as a fire-supporting grate 15, and the other of which serves as a broiling grill 43.

All of the plates except the grills are formed from relatively thin sheet metal. The vertical side edges of the back plate 11 and the front plate 12 are turned outwardly, inwardly, and backwardly to form relatively square, hollow beads 16 extending vertically on each side of each of these members.

These vertical, hollow beads are slid into sim-

2

ilarly shaped receiving channels 17, formed by rolling the front and back edges of the side plates 10, as shown in Fig. 4. This construction securely locks the members 10, 11, and 12 together by a simple, easy, sliding motion.

The side plates 10 are cut away along their lower portions, as shown at 18, for the admission of primary combustion air. These two plates are exactly similar in construction, and each carries three vertically spaced and vertically aligned hook clips 19 along its vertical, medial line secured thereto by means of suitable rivets 20, or in any other desired manner. The upper edges of the side plates are rolled outwardly to form outwardly-extending stiffening flanges 21, and the lower edges are rolled inwardly to form foot flanges 22.

The back plate 11 contains a smoke opening 23 surrounded by a smoke stack collar 24 adjacent its upper extremity. The back plate also carries three pairs of hooked clips 25 riveted or otherwise secured to its inner surface, each in horizontal alignment with one of the three clips 19 on the side plates. The back plate 11 is flanged outwardly at the top to form a top stiffening flange 36 and a bottom stiffening flange 37.

The top of the front plate 12 is flanged outwardly to form a top stiffening flange 34, and is flanged inwardly at the bottom to form a bottom stiffening flange 35. The front plate 12 is provided with a draft opening controlled by means of a vertically slideable door 26 operating in door guides 27, and also contains a fire door 28 mounted thereon upon suitable hinges 29 at the bottom of the door. The door 28 is provided with a swinging latch 30 by means of which it may be locked in the closed position by engaging a keeper 31. The door is also provided with a sliding damper 32 which controls secondary air openings 33.

The ash pan 13 is provided with a downwardly extending peripheral flange 38, which fits into the embrace of the hooked clips 19 and 25 adjacent the bottom of the stove, and with a convenient handle 39 by means of which it may be readily lifted from or placed in position.

The grills 15 and 42 are identical and each consists of a plurality of longitudinally extending, parallel rods welded at their extremities to transverse angle members 40. A stiffening rod 41 is welded across the middle portion of all of the rods and terminates in downwardly extending angle clips 42.

The top plate 14 consists of a smooth sheet

metal plate with its edges rolled downward and inward, as shown at 44.

It will be noted that all of the eight parts of the stove are relatively flat and can be piled upon each other and tied in a convenient flat bundle for transportation or storage.

To erect the stove, the beads 16 of the front and back plates 11 and 12 are slid down the channels of the two side plates 10 to form an enclosed structure. The ash pan 13, the fire grill 15, and the broiling grill 43 are put in place in the clips 19 and 25 to rigidly maintain the four walls in rectangular relation. The top or frying plate 14 is then slid over the top of the broiling grill 43, as shown in Fig. 2, and the stove is ready for use. For broiling meat, etc., the plate 14 may be completely removed, as shown in Fig. 1, or may be simply pulled back to expose a sufficient area of the broiling grill 43.

To dismantle the stove, it is only necessary to slide the top plate from place, and then lift the grills and the ash pan 13 from place. The two end members then can be easily slid from engage with the side members.

While a specific form of the improvement has been described and illustrated herein, it is desired to be understood that the same may be varied, within the scope of the appended claim, without departing from the spirit of the invention.

Having thus described the invention, what is claimed and desired secured by Letters Patent is:

A collapsible stove comprising side walls and front and rear walls, all formed of sheet metal, said side walls having lower end portions cut to form longitudinally extending recesses constituting air inlets and all of said walls having upper and lower edge portions bent laterally and forming inwardly extending lower flanges and outwardly extending upper flanges, said sides having front and rear end portions bent inwardly to form vertically extending tubular channels each open along its inner side, the front and rear walls hav-

ing side edge portions bent outwardly to form vertically extending hollow tubular beads fitting snugly in the channels through the open sides thereof and cooperating with the channels to detachably hold the walls together and reinforce corners of the stove, said front wall having a lower ash pit opening and an upper fire opening, doors movable into and out of closing relation to said openings, upper, lower and intermediate sets of clips secured against inner surfaces of said walls and having upwardly projecting bills spaced from the walls, an ash pan and a grate and a grill fitting within the stove and having depending marginal flanges engaging between the walls and the bills and thereby removably supported, the ash pan and the grate being flush with lower edges of the openings in the front wall and the grill flush with the upper flanges of all of the walls, and a removable top plate of sheet metal having side edge portions bent downwardly and inwardly to form side flanges engaging under and upper flanges of the side walls and its front end bent downwardly and rearwardly to form a front flange engaging under and upper flange of the front wall when the top plate is slid rearwardly along the side walls to a position at rest upon the grill closing the top of the stove and disposing its rear end upon the upper flange of the rear wall.
